*Primary Examiner—Stella Reid**Attorney, Agent, or Firm—Laney, Dougherty, Hessin & Beavers***[57] CLAIM**

The ornamental design for a tongue depressor or the like, as shown and described.

DESCRIPTION

FIG. 1 is a top perspective view of a tongue depressor or the like, showing my new design;

FIG. 2 is a bottom perspective view thereof;

FIG. 3 is a right side elevational view thereof, the left

side elevational view being a mirror image thereof; and,

FIG. 4 is a top plan view thereof.
